UNITED STATES PATENT OFFICE

157,030

SUPPORT RACK

Earl C. Chatfield, Oak Park, Ill.

Application June 19, 1947, Serial No. 140,144

Term of patent 14 years

(Cl. D33—3)

To all whom it may concern:

Be it known that I, Earl C. Chatfield, a citizen of the United States, residing at Oak Park, in the county of Cook and State of Illinois, have invented a new, original, and ornamental Design for a Support Rack, of which the following is a specification, reference being had to the accompanying drawing, forming part thereof.

Figure 1 is a plan view of a support rack, showing my new design;

Figure 2 is a front view of the support rack shown in Figure 1; and

Figure 3 is an end view of the support rack of Figure 1.

The dominant feature of my design for a support rack is illustrated by those portions shown in solid lines.

I claim:

The ornamental design for a support rack, as shown.

EARL C. CHATFIELD.
